UNITED STATES PATENT OFFICE.

EDWIN D. BANGS, OF MILWAUKEE, WISCONSIN.

GAS-ENGINE STARTER.

1,077,386.

Specification of Letters Patent.

Patented Nov. 4, 1913.

Application filed August 20, 1910. Serial No. 578,092.

To all whom it may concern:

Be it known that I, EDWIN D. BANGS, a citizen of the United States, and resident of Milwaukee, in the county of Milwaukee and State of Wisconsin, have invented certain new and useful Improvements in Gas-Engine Starters; and I do hereby declare that the following is a full, clear, and exact description thereof.

10 The object of my invention is to provide a simple, economical and positively actuated automatic starter for multiple cylinder gas engines, its construction and arrangement being such that an auxiliary charge of carbureted air is maintained under valve-control, having actuating mechanism in timed relation with motion of the engine, whereby said charge is admitted to that engine cylinder the piston of which is in a position just 20 past its highest compression point, and is ignited in the usual manner to impart initial motion to the engine.

With the above object in view the invention consists in certain peculiarities of construction and combination of parts as fully set forth hereinafter with reference to the accompanying drawings and subsequently claimed.

The drawing illustrates a diagrammatic view, partly in section, of an engine equipped with a starting apparatus embodying the features of my invention.

Referring by characters to the drawings, 1, 1^a, 1^b represent the cylinders, 2 the pistons 25 and 3 the crank-shaft of any standard type of internal combustion engine, the pistons in this instance three in number, being connected in the usual manner to the crank-shaft by pitmen 4, it being understood that 40 the crank portions of the shaft are set equal distances apart with reference to the axis thereof.

6 represents a valve-casing provided with an upper chamber 7 having a series of ports 45 8 each communicating with a separate lower compartment of the casing, the ports being normally closed by spring-controlled valves 9 having stems 10 that are suitably guided in the casing, the lower ends of which stems 50 are arranged to be engaged by cams 11 that are carried by an arbor 12 journaled in said valve-casing.

The arbor, as shown, is provided with a large sprocket-wheel 13 that is in link-belt 55 connection with a sprocket-pinion 14, which sprocket-pinion is secured to the crank-

shaft of the engine, said sprocket-pinion being of approximately half the diameter of the arbor sprocket-wheel, whereby two revolutions of the engine crank-shaft will impart 60 one revolution to the arbor. This arrangement of gearing, however, forms no part of my invention as the arbor may be geared in any other suitable manner to the engine shaft or to the "timer" (not shown), the essential feature in connection with the drive being that the arbor should rotate in timed relation with the engine crank-shaft in proportions of one to two.

Each port 8 is connected to the compression chamber 15 of one of the series of cylinders by a pipe or duct 16, these ducts being provided with check-valves 17, whereby they are controlled. A closed reservoir 18 is also provided, into the bottom portion of 75 which reservoir is fitted a wire screen 18^a that covers a layer of metallic shavings 19, there being a small quantity of gasoline or other volatile oil placed in the bottom of the reservoir from time to time through a filling 80 nipple 27. This reservoir thus equipped comprises an auxiliary carburetor which is connected to the compression chamber 15 of one of the cylinders by a pipe or duct 21, the latter being provided with a check-valve 22 85 and a controlling cock 23. The reservoir is also connected by a pipe or duct 24 to the chamber 7 of the valve-casing 6, the said pipe or duct being also provided with a check-valve 25 and controlling cock 26 as 90 shown.

From the foregoing description it will be seen that there is a valve-controlled port in the chamber 7 for each engine cylinder, it being understood that the number of cylinders and valve-controlled ports are immaterial to the operation of the starter and that the valve-casing 6 may be located at any convenient point relative to the engine as well as the reservoir 18. The controlling 100 valves 23 and 26 of the ducts 24 and 21, however, should be so placed, if the engine is used in connection with a self-propelled vehicle, that they are accessible to the operator. It should also be understood that 105 the engine is equipped with any standard type of spark ignition mechanism, which mechanism forms no part of my invention.

In the operation of my starting apparatus, should the engine be in motion and the operator desire to set the starter, the cock 23 110 would be opened, this cock, being in the duct

that communicates with the first cylinder 1^b and the reservoir, would thus open said duct and as the engine rotated the compressed charges of cylinder 1^b would be forced into 5 the reservoir 18 until the indicator gage carried thereby showed the desired pressure therein. The operator would then close cock 23 and the carbureted air which had been pumped therein from the cylinder 1^b would 10 be further enriched by the oil contained in the bottom of said reservoir. Valve 26, it should be understood, is at this time also closed and all three of the engine cylinders will now be operating as under ordinary 15 conditions. Should the engine come to rest and the operator desire to start the same, controlling cock 26 would be opened, thus permitting a charge of compressed carbureted air from the reservoir to fill chamber 20 7 of the valve-casing. Owing to the fact that the arbor cams are so disposed about said arbor that one of the valves 9 is at all times open, this charge of carbureted air would find its way through the 25 open port 8, and, as shown in the diagram, the carbureted air in this instance would pass from the open port to the first cylinder 1^b and, being under compression, the charge would be exploded by closing the spark 30 circuit, not shown, which circuit is closed just after a full charge has passed the check valve 17, whereby back firing into that portion of the charge remaining in the pipe 16 and valve casing is avoided. Owing to the 35 timed relation between the cam-carrying arbor 12 and the crank-shaft, when any one of the ports 8 are opened, the piston of the engine cylinder to which it is connected is just past its highest point and hence when 40 the explosion takes place the engine is

started, after which the operator closes valve 26, whereby communication is cut off between the reservoir 18 and the valve-chamber 7. The first cylinder 1^b will then act, as previously stated, as a pump for re- 45 charging the reservoir, it being understood that any one of the series of cylinders may be utilized for this purpose and that during the charging operation, the ignition mechanism is cut off from said cylinder 1^b. 50

I claim:

In a gas-engine having a series of cylinders, a piston reciprocative in each cylinder, and a crank shaft having the cranks thereof in rod connection with the pistons; the combination of a starting apparatus comprising a casing having an upper chamber and separate lower compartments, self-seating valves controlling ports by which communication is established between said chamber and compartments, an arbor provided with cams by which to actuate said valves, gearing connecting the crank-shaft and arbor, a reservoir in check-valve controlled communication with the compression chamber 60 of one of said cylinders and with the upper chamber of said casing, means for cutting off the reservoir from said cylinder and chamber, and a check-valve controlled duct leading from said casing-compartments to 65 the aforesaid cylinders.

In testimony that I claim the foregoing I have hereunto set my hand at Milwaukee in the county of Milwaukee and State of Wisconsin in the presence of two witnesses. 70 75

EDWIN D. BANGS.
